DESIGN FOR A PERFUME BOTTLE DISPLAY UNIT OR SIMILAR ARTICLE

John D. Buckingham, Chicago, Ill., assignor to Lucien Lelong, Inc., Chicago, Ill., a corporation of Illinois

Application August 29, 1940, Serial No. 94,718

Term of patent 7 years

To all whom it may concern:

Be it known that I, John D. Buckingham, a citizen of the United States and a resident of the city of Chicago, in the county of Cook and State of Illinois, have invented a new, original, and ornamental Design for a Perfume Bottle Display Unit or Similar Article, of which the following is a specification, reference being had to the accompanying drawing, forming a part thereof.

On the drawing:

Figure 1 is an elevational view of the perfume bottle display unit, or similar article, showing my new design;

The two sides not illustrated in Figure 1 are the same as the side illustrated.

I claim:

The ornamental design for a perfume bottle display unit or similar article, as shown and described.

JOHN D. BUCKINGHAM.
